UNITED STATES PATENT OFFICE

2,221,348

APPARATUS FOR TREATING METALLIC STRIP

John R. Hershey, Gary, Ind., and James K. Lamoree, Chicago, Ill.

Application March 15, 1937, Serial No. 131,062

1 Claim. (Cl. 15—3)

This invention relates to metallic strip and more particularly to the cleaning and polishing thereof.

With the advent, in recent years, of a marked increase in the demand for, and consequent production of, wide thin metallic strip in long lengths, the problems of handling such materials have likewise become increasingly acute. The coating of continuous metallic strip, such as with tin and terne, is rapidly becoming commercially practicable. The heretofore tried and proved methods of coating and subsequent cleansing and polishing of metallic strip in the conventional short lengths must be discarded when considering the treatment of unlimited lengths of the same material. That is to say, cleaning and polishing devices for short sheets have no difficulty in applying the cleaning medium to both sides thereof due to the fact that it can be fed to the upper surfaces and permitted to fall between successively fed sheets onto the device which applies it to the lower surfaces. However, continuous strip will not permit the cleaning medium to fall from above onto the device which applies it to the lower surface.

It is among the objects of the present invention to rapidly and uniformly clean and polish both sides of metallic strip of unlimited length.

The foregoing and other objects will be apparent after referring to the drawings, in which:

Figures 1 and 1^a are a plan, broken on the line X of a continuous coating and cleaning unit which embodies the apparatus of the present invention;

Figures 2 and 2^a are a sectional elevation, broken on the line Y, of the apparatus of Figures 1 and 1^a;

Figure 3 is a plan of the apparatus of the invention;

Figure 4 is a sectional view on the line IV—IV of Figure 3;

Figure 5 is a sectional view on the line V—V of Figure 3; and

Figure 6 is a sectional view illustrating a detail of the apparatus of the invention.

Referring more particularly to the drawings, the numeral 10 designates a coil of wide and relatively thin metallic strip S of unlimited length. Referring to Figures 1 and 1^a, and 2 and 2^a, this coil 10 is suitably mounted on a stand 12, and unwound and moved from right to left passing initially through a conventional tensioning stand A which is made up of a pair of driven pinch rolls 13, a relatively spaced roll 13^b and an intermediate disposed counterweighted roll 13^a. This

tensioning stand A is, accordingly, constructed and arranged to hold the strip S in a taut and flat condition.

The strip in this condition is then passed under a wooden roller 14 which is immersed in the acid in an acid tank B, whereby the strip is pickled. Following the pickling operation, the taut strip S is then passed over an elevated wooden roll 15 and under a wooden roller 16 which is immersed in the rinse water in a rinse tank C.

The strip S is pulled through the acid and rinse tanks B and C, respectively, by a pair of pinch rolls 18 which are driven by a suitable motor 19.

At the outlet side of the driven pinch rolls 18 there is disposed a coating machine D which contains a suitable coating medium, such as molten tin or the like. At its entrance, or introductory side, the coating machine D is provided with a pair of guide rolls 23, and a trough 24 containing a suitable molten fluxing medium through which the strip S is passed prior to its immersion in the coating medium. The strip S is guided upwardly out of the coating medium between a series of squeeze rolls 25 which are driven by a motor 27 and immersed in a solidification-promoting medium, such as a palm oil mixture.

Between the driven pinch rolls 18 and the guide rolls 23 of the coating machine D, there is disposed a limit switch 20 having an operating arm 21 below and adjacent the path the strip S is intended to follow. This limit switch 20 is suitably connected to a motor 22 which drives the pinch rolls 13, the arrangement being conventional and such that the depression of the operating arm 21 retards the speed of the pinch rolls. Therefore, if the strip S sags between the rinse tank C and coating machine D, the speed of feed of the strip will be decreased until the proper relationship is established.

As the coated strip S emerges from the coating machine D, it is passed over a counterweighted roll 28 and into a wash tank E which contains a weak solution of a suitable alkali, such as soda, and serves to further cool the coated strip and remove some of its palm oil coating. This wash tank E is made up of a pair of spaced wooden rolls 30, a plurality of intermediately disposed cleaning rolls 37, and a plurality of squeeze rolls 39 at the delivery or exit side thereof. Preferably the pairs of rolls 37 and 39 are made up of one flannel roll and one metal roll.

After the strip S emerges from the squeeze rolls 39 of the wash tank E, it is passed into the

novel cleaning and polishing, or scrubbing, machine F of the invention. Referring to Figure 3 of the drawings, this novel cleaning and polishing, or scrubbing, machine F comprises a shallow tank 60 having a deepened hopper 61 at the delivery or exit end thereof. This shallow tank 60 is mounted on legs 62 of suitable height.

Within the shallow tank 60 there is journaled a series of spaced-apart horizontally aligned cloth covered cleaning rolls 65, 66, 67, 68, 69 and 70, and a series of superposed spaced-apart horizontally aligned cloth covered cleaning rolls 75, 76, 77, 78, 79 and 80 for cooperation therewith. An introductory conveying roll 64 is journaled in the shallow tank 60 adjacent the cloth covered cleaning roll 65 and a delivery conveying roll 71 is journaled in the shallow tank 60 adjacent the cloth covered cleaning roll 70. One end of each of the rolls 75 and 77 carries a sprocket, as shown at 82 and 84, respectively. These sprockets 82 and 84 are connected by a chain 83. Each of the rolls 66, 77, 68, 79 and 70 carries a sprocket as at 86, 87, 88, 89 and 90, respectively. A shaft 93 is journaled beneath the shallow tank 60 and carries an idler sprocket 94 which is connected to the sprockets 86, 87, 88, 89 and 90 on the rolls 66, 77, 68, 79 and 70, respectively, by a chain 95.

A shaft 97 is journaled beneath the shallow tank 60 and carries a sprocket 98. This sprocket 98 is connected by a chain 100 to a sprocket 99 which is carried by the roll 70.

A motor 102 is disposed adjacent the cleaning and polishing, or scrubbing, machine F and provided with reduction gearing 103 with which there is connected a sprocket 104. This sprocket 104 is connected by a chain 105 to a sprocket 106 on the shaft 97.

From the foregoing it will be seen that the motor 102 drives the cloth covered cleaning rolls 75, 77, 66, 68, 79 and 70.

Referring again to Figure 3, each of the cloth covered cleaning rolls 65, 76, 67, 78, 69 and 80 carries a sprocket, as at 110, 111, 112, 113, 114 and 115, respectively. The introductory conveying roll 64 carries a sprocket 116 and the delivery conveying roll 71 carries a sprocket 117, as shown in Figure 4.

An idler sprocket 118, mounted on a shaft 93 journaled beneath the shallow tank 60 is connected by a chain 119 with the sprockets 110, 111, 112, 113, 114, 115, 116 and 117 on the rolls 65, 76, 67, 78, 69, 80, 64 and 71, respectively.

The delivery conveying roll 71 carries a large sprocket 120 which is connected to a small sprocket 121 on the shaft 97 by a chain 122. Therefore, the introductory conveying roll 64, cloth covered cleaning rolls 65, 76, 67, 78, 69 and 80, and the delivery conveying roll 71 are all driven by the motor 102, but at a slower speed than the cloth covered cleaning roll 66, 77, 75, 68, 79 and 70. This arrangement provides a very efficient scrubbing action.

Between the cloth covered cleaning rolls 65 and 75 and the introductory roll 64, there is disposed a vertically extending housing 125 having an upper adjustable feed orifice 126. Each side of the housing 125 is provided with a horizontal slot 127 to permit the passage of a strip therethrough. Within the housing 125 there is journaled a pair of spaced-apart vertically parallel double screw spiral conveyors, as shown at 128 and 129. Referring to Figure 6, these double screw spiral conveyors 128 and 129 are identical,

both being constructed to feed outwardly in both directions from their mid-portions if rotated in the same direction. However, they rotate oppositely and therefore the lower double screw spiral conveyer feeds the cleaning medium inwardly toward its mid-portion while the double screw spiral conveyer functions conversely.

The double screw conveyers 128 and 129 carry a pair of intermeshing gears, as shown at 130 and 131. The lower double screw spiral conveyer 10 128 carries a sprocket 132. A shaft 135 is journaled below the introductory roll 64 and carries a sprocket 136 which is connected by a chain 137 to a sprocket 138 on a shaft 139 which is journaled adjacent the shaft 97. 15

This shaft 139 carries a large gear 140 which meshes with a similar gear 141 carried by the shaft 97. The shaft 135 carries a sprocket 142 which is connected by a chain 143 to the sprocket 132 on the lower double screw spiral conveyer 128. 20

Immediately over the deepened hopper 61 of the shallow tank 60 there is journaled a supplemental delivery roll 145 which carries a pair of sprockets 146 and 147. The sprocket 146 is connected by a chain 148 to a sprocket 149 on the 25 cloth covered cleaning roll 70. The extreme delivery or exit end of the cleaning and polishing, or scrubbing, machine F is provided with an extension 151 in which there is journaled a second supplemental delivery roll 152. This 30 second supplemental delivery roll 152 carries a sprocket 153 which is connected by a chain 154 to the sprocket 147 on the supplemental delivery roll 145.

Between the delivery roll 71 and the supplemental delivery roll 145, there is disposed a bottom guide 155 for the strip S, and immediately above the same a diagonally mounted rotary brush 156. The end of the diagonally mounted rotary brush 156, which is adjacent the cloth covered cleaning roll 80, carries a bevel gear 158 which meshes with a bevel gear 159 on the roll 80. Therefore, the rotary brush 156 is rotated oppositely from the cloth covered cleaning roll 80. 40

Referring to Figure 4, the cleaning and polishing, or scrubbing, machine F embodies a suction manifold generally indicated at 162. This suction manifold is constructed and arranged to permit the passage of the strip S therethrough at 50 a point which is between the supplemental delivery roll 145 and second supplemental delivery roll 152, and comprises lower and upper manifold sections 163 and 164, respectively. The lower manifold section 163 is shown as provided with a central partition 166, a pair of air passages 167 and 168 and a small orifice 169. The upper manifold section 164 is shown as provided with a central partition 170 and large and small orifices 171 and 172, respectively. 55

Within the deepened hopper 61 of the shallow tank 60, there is journaled a single screw spiral conveyer 174 which carries a sprocket 175. This sprocket 175 is connected by a chain 176 to a 65 sprocket 177 on the shaft 97. At the delivery or exit end of the single screw spiral conveyer 174 a vertical housing 178 is connected to the deepened hopper 61 of the shallow tank 60. This vertical housing contains a conventional bucket conveyer 70 (not shown) which is driven through a sprocket 180 and chain 181 from a sprocket 183 on the shaft 135. The top of the vertical housing 178 is provided with a delivery pipe 185 which communicates with the upper feed orifice 126 in the 75

vertically extending housing 125 which carries the double screw spiral conveyers 128 and 129.

In operation the coiled strip S is fed from the stand 12 and through the tensioning stand A, acid 5 tank B, rinse tank C, coating machine D, and wash tank E, in the manner previously mentioned, and then fed through the novel cleaning and polishing, or scrubbing, machine F. The introductory conveyer roll 64 of the cleaning and polishing, or scrubbing, machine F passes the strip through the horizontal slots 127 in the vertically extending housing 125. While passing through the vertically extending housing 125, the strip S is provided on both of its sides with bran, or 10 other suitable scrubbing medium, by the lower and upper parallel double screw spiral conveyers, 128 and 129, respectively. As previously mentioned, the function of the upper double screw spiral conveyer 129 is to feed the cleaning medium 15 from its mid-portion outwardly toward its ends, while the function of the lower double screw spiral conveyer 128 is to feed the cleaning medium from both of its ends inwardly toward its mid-portion. The strip S, thus provided on both 20 of its surfaces with the cleaning medium, is then passed through the cloth covered cleaning rolls 65 through 70 and 75 through 80. As the scrubbed strip S is fed from between the last pair of cloth covered cleaning rolls (70 and 80), it is 25 fed onto the delivery conveying roll 71 and over the bottom guide 155.

During its passage over the bottom guide 155, the upper surface of the strip S is contacted by the reversely rotating diagonally mounted rotary 30 brush 156, which functions to divert the cleaning medium therefrom, whereupon it is permitted to flow downwardly into the deepened hopper 61 at the delivery or exit end of the shallow tank 60. As the strip emerges from between the bottom 35 guide 155 and the reversely rotating rotary brush 156, it is passed onto the supplemental delivery roll 145, and through the suction manifold generally indicated at 162. As the strip S emerges 40 from this suction manifold, it is directed onto the second supplemental delivery roll 152, and out of the cleaning or scrubbing machine F.

After the cleaned and polished strip S is fed from the cleaning and polishing, or scrubbing, machine F, it is passed through a tensioning stand G which is made up of a canvas covered idle roll 170, a relatively spaced pair of rolls 172^a and 172^b, 5 and an intermediately disposed counterweighted roll 171. This tensioning stand G is, accordingly, constructed and arranged to hold the strip S in a taut and flat condition.

The strip in this condition is then passed to a 10 coiling machine H of any suitable design. After the strip S has been coiled by the coiling machine H, it may be further treated in any manner desired.

While we have shown and described one specific embodiment of the invention, it will be understood that we do not wish to be limited exactly thereto, since various modifications may be made without departing from the scope of the invention as defined by the following claim.

We claim:

In an apparatus for cleaning strip, a pair of superposed adjacent double spiral screw conveyers, each of said screw conveyers comprising opposed right-hand and left-hand screw portions 25 extending inwardly toward the center thereof, said screw conveyers being reversely rotatable, means for supplying a cleaning medium to the inner ends of the right-hand screw portion and the left-hand screw portion of the upper of said 30 screw conveyers, the upper of said screw conveyers being so rotatable as to move the cleaning medium toward the ends thereof, and a housing for said screw conveyers, said housing being constructed and arranged to permit intercommuni- 35 cation between said conveyers adjacent both of their corresponding ends, whereby the cleaning medium may be delivered outwardly toward and from the ends of the upper of said screw conveyers to the corresponding portions of the lower of 40 said screw conveyers, and said housing having a slot in its forward and rearward side walls to permit the passage of a strip therethrough and between said screw conveyers.

JOHN R. HERSHHEY. 45

JAMES K. LAMOREE.
